BUCKLE

John R. Reyburn, Fairfield, Conn., assignor to
American Chain & Cable Company, Inc., a
corporation of New York

Application October 7, 1937, Serial No. 167,736

10 Claims. (Cl. 24—193)

This invention relates to a strap buckle of the lever type adapted to be used more particularly in connection with emergency traction chains for vehicle wheels.

5 The main objects of this invention are to provide an improved buckle which is simple in construction, easy to manipulate and inexpensive to manufacture, and which continues to function properly independently of precise original dimensions of the strap and buckle parts and of changes effected by wear during service.

One known type of buckle comprises a buckle plate and a pivoted lever of the cam type. In this type of lever the cam bites into the strap as it presses the strap against the base during movement into locking position and when in locking position. The efficiency of this type of buckle depends upon refinements of manufacture not only of the buckle but also of the strap as resistance to withdrawal of the strap from the buckle depends upon the amount of bite of the cam lever into the strap. Such biting into the strap causes the strap to weaken and to fray at the points where the cam bites into the strap.

20 In such constructions it is also necessary to provide a relatively deep channel in the buckle plate to accommodate the cam of the lever and the strap which results in the creation of a space between the lever and the strap in which grit and snow and ice may accumulate thereby preventing an easy release of the strap from the buckle. As such lever is closed a relatively large loop is produced in the strap adjacent the pivot of the lever which, when the lever is locked by interposing the end of the strap between the lever and a projection on the buckle plate will prevent the lever locking elements from cooperating with the cam locking means unless and until there has been sufficient slippage through the cam locking 25 means to take up the slack created by the loop of the strap. In certain of these constructions the lever locking means comprises a transversely extending closed or interrupted loop through which the strap must be threaded, or with which it may be engaged with more or less difficulty by several reverse lateral movements and disengaged by reverse lateral movements, all of which will be difficult under actual conditions in service. Furthermore, grit and ice and snow will collect 30 in the loop portion of the strap whereby when the lever is moved into open position the strap will not be pushed back over the base of the buckle plate.

One of the more specific objects of this invention is to provide an improved buckle in which

the strap tensioning and holding functions do not depend upon any clamping action between the lever and the bottom of the base of the buckle plate whereby a greater tolerance may be allowed in the manufacture of the buckle and in the selection of the strap for use with the buckle.

Another object is to provide the lever with a strap receiving means and to so locate such means on said lever with respect to the bottom of the channel in the buckle plate, that the strap may be readily passed through said channel and threaded into said means when the lever is in full open position parallel with the buckle plate.

Another object of this invention is the provision of a lever locking lug overhanging one edge of the lever and between which and the lever a strap may be moved by simple lateral movements of the strap, together with means on the lever on opposite sides of the lug for holding 20 said strap under said lug.

Another object of the invention is the provision of a buckle which includes a more effective primary holding means the effectiveness of which increases with the increase of tension of the 25 strap.

Other objects of the invention will appear from the following description taken in connection with the drawings in which are shown several forms of the invention.

In the accompanying drawings;
Figure 1 shows one form of buckle applied to a tire chain shown mounted on a tire;

Fig. 2 shows in longitudinal section a strap threaded through the loop in the lever in fully 35 open position;

Fig. 3 shows in longitudinal section the strap and lever in midway position;

Fig. 4 is a detailed perspective view of the buckle showing the lever in locking position, with 40 the free end of the strap swung laterally prior to its being engaged with the locking lug on the buckle plate;

Fig. 5 is a view similar to Fig. 4 in which the strap has been moved into locking position between the lever and lug on the buckle plate and is about to be moved into locking engagement 45 with a slot in the lever;

Fig. 6 is a perspective view of a tire chain and 50 of the lever and strap in locking position;

Fig. 7 is a longitudinal section through the buckle and strap on line 7—7 on Fig. 6;

Fig. 8 is a top plan view of the lever and buckle plate with the strap removed;

Fig. 9 is an end view of the lever and buckle plate with parts of the buckle plate in section;

Fig. 10 is a top plan view of a modified form of the buckle;

5 Fig. 11 is an end view of the modification shown in Fig. 10;

Fig. 12 shows the lever in open position and the strap threaded through the loop in the lever;

10 Fig. 13 is a longitudinal section taken on the line 13—13 on Fig. 10 showing the lever in locking position;

Fig. 14 shows a top plan view of a second modified form of the buckle showing the lever in closed 15 position;

Fig. 15 is an end view of the buckle shown in Fig. 14;

Fig. 16 shows the lever in open position and the end of a strap threaded through slots in the 20 lever; and

Fig. 17 is a longitudinal section on line 17—17 of Fig. 14 showing the lever in locking position.

Referring to the drawings and first referring to Figs. 1 to 9 which disclose what may be considered the preferred form of my invention, in Fig. 1 there is disclosed by dot and dash lines the outline of a tire and felloe showing a tire chain 20 of any suitable construction secured in position on the tire by a buckle made according to 30 this invention.

The buckle comprises a buckle plate 21 which may be provided with a channel 22 providing side walls 23 and 24 forming a guide groove for the free end of a strap 25 the other end of which 35 may be secured in the usual manner to a plate 26 to which one set of ends of the cross chains 20 may be secured, as indicated in Fig. 6. The side walls 23 and 24 are preferably integral with laterally extended wings 27 and 28 to which the 40 opposite set of ends of the chains may be secured, as indicated in Fig. 6. The tensioning and locking lever indicated at 30 is preferably provided with laterally extending pintles 31 and 32 journaled in holes 31x and 32x in the walls 45 23 and 24. The pintle holes 31x and 32x are preferably located near the ends of the walls 23 and 24, as indicated in Figs. 8 and 9, and at a distance from the bottom of the base sufficient to accommodate the end of the strap 25 freely 50 as the end of the strap is threaded over the base of the channel in the buckle plate or removed therefrom, as indicated in Fig. 2. This distance is also such that there will never be any gripping or pressing action by the lever of the 55 strap against the base, as indicated clearly in Figs. 2, 3 and 7.

The wing 27 is provided with a locking lug 34 struck out of the side wall 23 and projecting over one side of the channel or guide groove 22 60 into the path of the locking lever 30 which lever is provided with a slot 34x to permit the lever to be moved below said lug, as indicated in Fig. 8. This lug may be wider at its base than at its free end for purposes of strengthening same and it 65 is preferably slightly inclined upwardly, as indicated in Figs. 4, 5, 8 and 9 to facilitate the movement of the strap into and out of locking position between the lever and the lug. The free end of the lever may be provided with a slot 30x 70 through which the strap may be passed and located, as indicated in Fig. 6, the walls 30y and 30z of said slot functioning as means for preventing disengagement of the strap from the lug 34.

75 For the purpose of causing the strap to hug

the end of the lever tightly as it is moved from its open horizontal position to its locking horizontal position the top portion of the rear or pivoted end of the lever, as viewed in Fig. 8, is provided with opposing ears 36 and 37 spaced 5 from the body of the lever to permit the free passage of the end of the strap therebetween and which are placed sufficiently close to the pivot on the lever to cause the strap to engage the end of the lever as the lever is moved from open 10 to locking position for the purpose of increasing the bite between the pivoted end of the lever and the strap. These ears also function to hold the strap under the lug 34. The end of the lever may be provided with teeth 38, as indicated in 15 Fig. 8.

The strap and buckle may be assembled as follows: In Figure 2 the lever is shown in open position and the end of the strap has been threaded through the channel in the buckle plate 20 and through the space between the ears 36 and 37 and the upper face of the lever. As clearly indicated in this figure, this may be freely done as the parts are proportioned so that the distance between the lever and the bottom of the 25 channel 22 and the distance between the ears 36 and 37 and the upper face of the lever are slightly greater than the thickness of the strap 25. The side walls of the channel provide means also for facilitating threading of the strap under the ears 36 and 37. After the strap has been threaded into the buckle, as shown in Fig. 2, the lever may be moved toward closing position, and as also indicated in Fig. 3 the lever may be moved with the strap in the full line position A 35 or the strap may be pressed on the lever and held in contact therewith as indicated in the dotted position B or it may be preferably engaged with the slot 30x in the end of the lever, as indicated in dotted position C. It will be 40 noted that when the lever is moved from the open position in Fig. 2 to the midway position in Fig. 3, the strap is immediately pulled and held against the end of the lever and that this biting contact of the lever on the strap causes 45 the lever to take up slack in the strap and tension the same.

As the lever is then moved from the midway position shown in Fig. 3 into the closed position, indicated in Figs. 1, 4, 5, 6, 7 and 8, the tensioning of the strap is continued. When the lever is in closed position the strap may be moved laterally to the left, as indicated in Fig. 4, to clear the locking lug 34 after which it may be moved laterally to the right into locking position under the lug 34. From this position the end of the strap may be moved farther to the right and then into alignment with the slot in the lever, as indicated in Fig. 5, and then moved to the left into the position shown in Figs. 6 and 7. In this position the walls of the slot 30x in the end of the lever act as a lock for the locking engagement provided by the lug 34. The ears 36 and 37 on the lever also hold the strap under the lug 34. The construction is such that when 65 the lever is moved into locking position, the portion of the strap between the free end of the lever and the pivoted end of the lever will be substantially taut immediately opposing any tendency of the strap to slip about the biting 70 edge of the lever as appears more clearly from Figs. 3 and 7.

To release the strap the operations before described for locking the lever in locking position, are reversed and disconnection between the strap 75

and buckle may be readily effected as is apparent. As shown in Fig. 7, the spaces between the strap, lever and buckle plate have been reduced to a minimum thereby preventing clogging of parts 5 with grit, sand, snow, ice and the like. As the strap is held in close contact with the pivoted end of the lever providing a very narrow U-shaped loop at this point it is obvious that when the lever is moved from locking to open position, 10 the size of the loop will not be increased and that the strap will be pushed rearwardly by movement of the lever without first having to reduce the size of the loop at this point.

As appears from the figures and description 15 given, it is clear that the efficiency of the buckle does not depend upon any refinements in construction, such as would limit tolerances either in the construction of the buckle or in the construction of the strap to be used therewith. It 20 is also obvious that the biting of the pivoted end of the lever on the strap is increased directly with the tension on the strap and is independent of the thickness of the strap, and that locking lug 34 immediately functions to prevent 25 the strap from slipping on the biting end of the lever.

The modification disclosed in Figs. 10 to 13 inclusive includes a buckle plate 40 provided with a guiding groove or channel 41 with horizontally flaring walls to provide for a wider section at the point of pivotal connection with the lever 42. The free end of the lever 42 is formed generally the same as the free end of the lever of the preferred form. Near its pivoted end the lever 42 is bent upwardly, as at 43, and downwardly, as at 44, when considered with respect to its locking position. The portion 44 is extended laterally and then upwardly to provide pivot lugs 45 and 46 which are provided with 30 apertures 47 and 48 to receive pintles 41x and 43x struck out from the ends of the side walls of the channel in the buckle plate 40. The lugs 45 and 46 are bent toward each other, as indicated to provide ears 49 and 50 constituting with the portion 44 an interrupted loop to receive the strap 45 25. The strap is assembled with the buckle in the same way as described in connection with Figs. 1 to 9, the open position of the lever being shown in Fig. 12 and the closed position being 50 shown in Figs. 10, 11 and 13. By forming the pintles on the buckle plate instead of on the lever it is possible to locate the ears 49 and 50 closer to the pivoted end of the lever to operate directly and immediately upon the strap 25 to bend the 55 same about the end of the lever during tensioning and locking operation and to push the strap rearwardly toward the entrant end of the channel upon initial movement of the lever from the locking position shown in Fig. 13. By inclining the interrupted loop with respect to the length 60 of the lever such operation is further facilitated. In this modification as well as in the preferred form the parts are constructed so that the strap will freely clear the bottom of the channel in 65 the buckle plate in any position of the lever.

In the modification disclosed in Figs. 14 to 17, the buckle plate 51 is of the same construction as the buckle plate 21 in the preferred form. The free end of the lever 52 and the overhanging lug on the base 51 are substantially the same as corresponding parts in the preferred form. The lever 52 at its pivoted end is provided with a V-shaped portion 53, the sides of which are provided with aligned slots 54 and 55 to receive the strap. The slots 54 and 55 are provided 75

with biting edges 54x and 54y and 55x and 55y respectively. These slots have the same function as the opposing ears 36 and 37 of the preferred form. Pintles 56 and 57 are formed on the end of the lever and are supported in openings 56x and 57x in the side walls of the channel in the buckle plate.

As shown in Fig. 16, the lever when in its fully open position will permit the strap to be threaded over the base of the channel in the buckle plate 10 and through the aligned slots in the V-shaped portion 53 of the lever. When the lever is swung toward closing position the pivoted end 58 of the lever and the walls of the aligned slots will frictionally engage and bite into the strap and 15 bend it around the end of the lever and tension it as will be apparent from the description of the lever in the preferred form. The free end of the strap is locked in position between the lever and the locking lug on the buckle plate by 20 engagement in a slot in the lever in the same way as in the other modifications.

All of the modifications disclosed show the same principle of construction and operation. In none of these is the securing and tensioning 25 function dependent upon any cooperation between the lever and the bottom of the channel in the buckle plate. The friction and biting created between the lever and the strap results from engagement between the strap and the portions of the lever through which it is threaded.

While I have shown and described a preferred embodiment of my invention and several modifications thereof, it will be understood that the principles of my invention may be incorporated 35 in still other embodiments, and that the disclosure herein made is to be taken as illustrative and not limitative and that I reserve the right to make various changes in form, construction and arrangement of parts without departing 40 from the spirit and scope of my invention as set forth in the accompanying claims.

I claim:

1. A strap securing device comprising a plate, a lever pivoted at one of its ends to said plate 45 for pivotal movement into a plane parallel to the plane of said plate in strap releasing and securing positions, and a strap receiving loop on said lever receiving the end of a strap passed across the plate when the lever is in strap releasing position and providing means for causing the strap to bite the end of the lever upon initial and continued movement of the lever as it is moved toward strap securing position.

2. A strap securing device comprising a plate, 55 a lever pivoted at one of its ends in spaced relation to said plate to provide for free passage of a strap between the lever and the plate when the lever is in strap releasing position, and strap receiving means carried by said lever in alignment with the space between the pivoted end of the lever and the plate when the lever is in strap releasing position, the location of the pivot connection of the lever with respect to its end being such as to provide for free movement of the strap 60 over the plate and free movement of the strap with the pivoted end of the lever as the lever is moved toward strap securing position.

3. A strap securing device comprising a plate, a lever pivoted at one of its ends to said plate 70 and mounted for movement into a plane parallel to said plate in strap releasing and securing positions, and strap receiving means on the lever extending toward the plate when the lever is in strap releasing position and away from the plate 75

- when the lever is in strap securing position, said means being so located with respect to the pivot and end of the lever as to cause the strap to bite the end of the lever and draw the strap forward as the lever is moved toward strap securing position, and to move the strap rearwardly across the plate to release the same as the lever is moved toward strap releasing position.
4. A strap securing device comprising a plate, a strap tensioning and strap securing lever, pivots on one end of said lever lying in the plane of the main body of the lever and its pivoted end and journalled in said plate, said pivots being so located with respect to the plate as to permit the strap to move freely with the lever over the plate in either direction, strap retaining means on said lever operable to bend the strap against the end of the lever as the lever is moved into strap securing position to take up and tension the strap and to push the strap in the opposite direction as the lever is returned to strap releasing position, and means on the plate and lever cooperating with the strap to lock the lever in strap securing position.
5. In a strap securing means, the combination of a plate, a locking lever pivoted near one of its ends to said plate, ears on the pivoted end of the lever provided with apertures to receive pintles on said plate, pintles on said plate, and oppositely facing extensions on said ears in the plane of said pintles providing a strap receiving loop at said pivoted end of said lever.
6. A strap securing lever comprising a flat bar, pintles projecting laterally from the side edges at one end of the bar, and strap receiving opposed ears formed on the side edges of said bar adjacent said pintles.
7. A strap securing lever comprising a flat bar provided at one end with a V-shaped portion extending transversely of the length of said bar,

apertured pivot ears formed on the leg of the V constituting the pivoted end of the link, and oppositely facing members on said ears constituting a strap receiving means in connection with said leg of said V.

8. A strap securing lever comprising a flat bar provided at one end with a V-shaped portion extending transversely of the length of said bar, the legs of said V being provided with alined strap receiving slots, and pintles formed on the free end of the leg of the V constituting the end of the lever.

9. A buckle comprising a plate, a lever pivoted at one end to said plate to be swung from strap releasing to strap securing position, a strap receiving loop on the rear face of said lever adjacent the pivoted end of the lever through which the free end of a strap passed across the pivoted end of the lever may be threaded, the relative sizes of said loop and strap being such the loop will frictionally engage the strap and bend it against the pivoted end of the lever as the lever is moved toward strap securing position, and means on the plate cooperating with the strap on the rear face of the lever for holding the strap against the lever and the lever in strap securing position.

10. A buckle comprising a frame, a lever pivoted at one end on the frame for movement between positions in which it secures a strap to the frame and releases a strap from the frame, a lug on the frame projecting into the path of said lever, said lever being notched to clear said lug as the lever is moved into strap securing position, and strap retaining means on said lever located between said notch and pivoted end for drawing said strap upon the pivoted end of the lever to tension the strap as the lever is moved from strap releasing into strap securing position.

JOHN R. REYBURN.
